UNITED STATES PATENT OFFICE.

HARALD J. VENNES, OF NEW YORK, N. Y., ASSIGNOR TO WESTERN ELECTRIC COMPANY, INCORPORATED, OF NEW YORK, N. Y., A CORPORATION OF NEW YORK.

GENERATING HARMONIC CURRENTS.

Application filed April 28, 1919. Serial No. 293,055.

To all whom it may concern:

Be it known that I, HARALD J. VENNES, a citizen of the United States, residing at New York, in the county of New York and State of New York, have invented certain new and useful Improvements in Generating Harmonic Currents, of which the following is a full, clear, concise, and exact description.

10 This invention relates to the generation of electric currents and has for an object the production of harmonic currents from a source of alternating voltage.

15 A feature of the invention relates to a circuit arrangement whereby harmonics are generated effectively by the use of an electron discharge relay.

20 This invention relates to a means of and method for producing harmonics from an impressed electromotive force of preferably substantially sinusoidal wave form. The apparatus is termed a harmonic producer and is of general application in the electrical arts. It is herein considered in connection 25 with a transmission system as a generator or regenerator, according as it is adapted to produce harmonic currents for transmission purposes, or to supply corresponding harmonics for reception or retransmission 30 purposes. According to the preferred form of this invention, the impressed wave is given a marked distortion in one half-cycle, while it is repeated more nearly true to form in the opposite half-cycle by taking 35 advantage of the irregular characteristic of an electron discharge device when provided with a suitable high resistance in its output circuit. The output current of the electron discharge device will therefore have 40 a distorted or non-sinusoidal wave form, which may be resolved into a fundamental frequency component and a series of sinusoidal harmonics. By suitable circuit arrangements, these harmonic currents may be 45 applied to a work circuit, and, if desired, may be amplified.

50 Reference is made to the drawings, in Figs. 1 and 2 of which are given curves showing operating characteristics of a thermionic device according to the invention, and Fig. 3 illustrates diagrammatically a circuit arrangement for the production of harmonics according to the present invention.

From the curve 1 which represents the

normal characteristic curve of a thermionic relay, it is seen that along only a relatively short portion of the curve in the region representing zero potential on the grid will a given change of grid potential in the negative and in the positive direction produce substantially equal variations in plate current above and below a mean value. When the grid potential is varied over a comparatively wide range, the plate current variations do not correspond precisely, and advantage may be taken of this fact to secure a non-sinusoidal plate current by impressing a sinusoidal electromotive force of sufficient magnitude. This action has been 60 called overloading the tube, and the distorting effect depends upon the limited supply of electrons present in the electron tube, available for conveying current across the discharge space.

75 According to the present invention a characteristic shown as curve 2 is secured, in which the distortion is very pronounced, and which is particularly adapted to the production of harmonics on account of the 80 abrupt break in the portion of the curve indicated by A. The reason for this bend in the curve is primarily that the internal resistance is of such a small value relative to the large external fixed resistance that the 85 later predominates in controlling the amplitude of the plate current. In Fig. 2 are shown the characteristic curve 3 and a curve 5 giving the form of wave produced in the output circuit by an impressed potential of 90 sine wave form indicated by the dotted curve 4. It is seen that the portion of curve 5 below the normal amplitude line is substantially sinusoidal, while the upper portion is much distorted. By analysis, it is found 95 that the output wave thus obtained contains both even and odd harmonics, in about the same proportion.

100 Referring to Fig. 3, current from a sine wave generator 6 of base frequency is supplied through line 7 to the primary 8 of a step-up transformer, the secondary 9 of which is connected to the input terminals of a thermionic amplifier 10. The amplifier 10 comprises an evacuated container or tube 105 containing a hot filament 11, or other electron source, a plate or anode 12 and a grid or impedance controlling element 13. A battery 14 may be used to fix the normal potential of the grid 13. The filament 11 may be 110

heated by current from a battery 15 regulated by the variable resistance 16. The amplifier is provided with plate current from a battery 17, connected to the filament 11, 5 and to the plate 12 through an impedance 18, which acts to exclude the variation current component from this path. The output circuit of amplifier 10 is traced through a condenser 19 of large capacity to the grid 21 of 10 the harmonic generator or regenerator 20, which has a hot cathode or filament 22 connected to the filament 11 and supplied with heating current from the battery 15. A switch 20' is shown whereby the normal potential of the grid relative to the filament 15 may be made zero as in the position shown, or may be made positive or negative by throwing the switch to one or the other of the other positions indicated. Connected across 20 the filament 22 and grid 21 is a parallel resonant circuit 26 consisting of an inductance and a capacity tuned to the base frequency, so that this path offers practically infinite impedance to the base frequency current, 25 but low impedance to any harmonics which may have passed the amplifier 10. The result is that a substantially pure sinusoidal wave is impressed upon the harmonic generator or regenerator 20. Condenser 19 acts 30 as a blocking condenser to prevent flow of current from battery 17 through path 26 and back through the impedance coil 18.

The harmonic producer 20 comprises an evacuated tube containing, in addition to the 35 grid 21 and filament 22 already mentioned, an anode or plate 23. Plate current is supplied from battery 17, connected to the filament 22, and to plate 23 through an impedance coil 24, similar to impedance coil 18, and 40 a large ohmic resistance 25, which may be inductive or non-inductive. Coil 24 may be omitted, especially if the resistance 25 is inductive. This resistance 25 is large compared with the normal output impedance of 45 the tube, values of the order of from 6000 ohms to 48000 ohms having been used, depending upon operating conditions, where the normal internal output impedance of the tube was of the order of 4000 or 5000 ohms. 50 The smaller value of resistance mentioned was used in a particular case in which the base frequency current supplied to the harmonic generator was relatively strong, and the large value was used when the incoming 55 base frequency current was weak and it was found advantageous to bring the break in the characteristic of the generator well within the range of the small impressed potential. These values are given by way of illustration, 60 only and are not to be construed as in any sense limiting the invention. Resistance 25, in addition to giving the highly advantageous characteristic for the production of harmonics, performs the additional function 65 of greatly stabilizing the output circuit, since

when the tube is highly conducting, i. e., when the distortion occurs and therefore when the harmonics are being produced, the impedance of the circuit is practically the impedance of the exterior portion of the circuit, and small fluctuations in the tube impedance, such as are often occasioned by an exchange of tubes, have negligible effect upon the production of harmonics. 70

The output circuit of the harmonic generator 20 leads through the condenser 27 of large capacity to the grid 28 of a thermionic amplifier 30, which has a hot cathode or filament 29 connected to filament 22 and supplied with heating current from the battery 15. A battery 31 is used to fix the normal potential of the grid 28. Condenser 27 acts as a blocking condenser to prevent flow of current from battery 17 through the path 24, 25, and back through the inductance 34, mentioned hereinafter. In the evacuated enclosure of amplifier 30, besides the grid 28 and filament 29 already mentioned, is a plate 32 connected to the plate battery 17, through impedance coil 33, which acts similarly to impedances 18 and 24, to prevent flow of variation current components in the plate battery circuit. Across the input terminals of the amplifier 30, an inductance 34 is connected, which offers low impedance to the base frequency current component, but high impedance to the harmonics which appear in the output circuit of the harmonic generator 20. The harmonics are therefore impressed on the amplifier 30, and after passing through the amplifier, they are led through a condenser 35 of large capacity to the primary 36 of a suitable transformer, the secondary 37 of which may be connected to the desired work circuit. 100

Although an exact explanation of the action of the resistance 25 is not essential to enable one to practice this invention, the following explanation is believed to be correct and may assist somewhat in an understanding of the invention. It is not intended as a limitation on the invention, which is independent of the theory of operation. 110

The space current circuit comprises in series the space current source, the large 115 fixed external resistance and the variable internal resistance of the tube. This latter resistance approaches a zero value as the grid potential increases. As the internal resistance approaches zero the space current approaches the limiting value determined by the fixed external resistance. Accordingly, the bend in the characteristic curve must occur between this limit when the effect of the external resistance preponderates 120 and the other limit when the internal resistance is large enough to cause its effect to preponderate. That this bend due to the effect of the large external resistance becomes comparatively sharp as the horizon- 125 130

tal portion of the curve is approached follows from the fact that with a uniform rate of decrease of the internal resistance, the rate of change of the ratio of external to internal resistance progressively increases. It should be noted also that the effect produced by the external resistance and the ordinary so-called saturation effect are additive, which increases the sharpness 10 of the bend in the characteristic curve.

Although the invention has been illustrated and described in connection with a specific circuit arrangement, it is to be understood that it is not to be limited either 15 to the specific arrangement as a whole or to its particular details, but only by the scope of the appended claims.

What is claimed is:

1. The method of generating harmonics 20 in a system comprising in combination a source of alternating electromotive force, an electric discharge repeating device having a cathode, an anode and an impedance control element, and a high resistance in the 25 output circuit of the repeating device, which method consists in impressing on the repeating device from said source cyclically varying voltage which alternates between limits chosen to include the knee of the 30 characteristic curve of said repeating device.

2. A method of generating harmonics in a system comprising in combination an electron discharge repeater having an anode, a 35 cathode, an impedance control element, an input circuit, an output circuit and a high resistance in the output circuit, which method consists in impressing on the input circuit of the repeater a cyclically varying 40 voltage and a constant voltage, the sum of said voltages alternating between limits chosen to include the knee of the characteristic curve of said repeater.

3. A generator of harmonics comprising 45 an electric discharge repeating device having a cathode, an anode and an impedance

control element, a source of substantially constant alternating potential connected to said cathode and said impedance control element, and a direct current source and a 50 large impedance serially connected to said cathode and anode, the amplitude of said alternating potential being sufficient to cyclically overload said device.

4. A generator of harmonics comprising 55 an electric discharge repeating device having a cathode, an anode and an impedance control element, a source of substantially constant alternating potential and a polarizing source serially connected to said cathode 60 and impedance control element, and a direct current source and a large resistance serially connected to said cathode and anode, the combined potential from said alternating potential and polarizing sources being 65 such that the electric discharge repeating device is cyclically overloaded thereby.

5. A generator of harmonics comprising 70 an electron discharge repeater comprising an electron discharge device with an anode, a cathode and an impedance control element, an input and an output circuit for said repeater, a source of substantially constant alternating potential and a polarizing source connected to said input circuit, a 75 source of space current and an impedance of element large compared to the minimum internal impedance of said device connected serially in said output circuit whereby angular configuration is given to the characteristic curve representing the relation between the potential of the impedance control element with respect to the cathode and the space current, the potentials impressed from said alternating potential and 80 polarizing sources being such that operation occurs over that part of said characteristic curve which includes the angular portion. 85

In witness whereof, I hereunto subscribe my name this 24th day of April A. D. 1919.

HARALD J. VENNES.
